UNITED STATES PATENT OFFICE.

FREDERICK A. VOIGT, OF CHICAGO, ILLINOIS.

SAFETY DEVICE FOR SCAFFOLD WORKMEN.

1,127,832.

Specification of Letters Patent.

Patented Feb. 9, 1915.

Application filed October 3, 1914. Serial No. 364,904.

To all whom it may concern:

Be it known that I, FREDERICK A. VOIGT, a citizen of the United States, residing at Chicago, in the county of Cook and State of Illinois, have invented a new and useful Improvement in Safety Devices for Scaffold Workmen, of which the following is a specification.

The object of my invention is to provide a device for safeguarding workmen on scaffolds, such as are hung by ropes from the roofs of buildings undergoing painting, repairs and the like.

A scaffold of the kind referred to is usually suspended at its ends by ropes hooked on the roof, and it is common practice to hang, in the same way, guide-ropes, one for each workman on the stage to hang across the latter. The workman is supposed to keep hold of the guide-rope with one hand while performing his work with the other, so that if the scaffold should fall he may save himself by clinging to and sliding down the guide-rope. As experience shows, however, workmen frequently neglect to observe this precaution, with the result that they frequently incur accidents through falling of the scaffolds.

My safeguarding device is flexibly hung on a belt to encircle the workman's body, and it involves, generally described, a clencher-tube to loosely surround the guide-rope and enable it to slip readily along the latter and thus avoid hampering the movements of the workman on the scaffold stage or platform, the tube being adapted to automatically grip the guide-rope in the event of the workman falling with or off the scaffold and hold him securely until he can right himself to slide down the rope to safety.

In the accompanying drawing, Figure 1 is a perspective view showing the belt and the clencher-tube thereon for surrounding the guide-rope; Fig. 2 is a view in side elevation showing the tube in its preferred form; Fig. 3 is a section on line 3, Fig. 2; Fig. 4 is an enlarged section on line 4, Fig. 3, representing the clencher-tube on the guide-rope, shown dotted, and Fig. 5 is a view of the clencher-tube in rear elevation.

The belt 5, of leather, or other suitable material, is shown to be adapted to be buckled about the body, as the waist, of the user of the device. It carries a flexible hanger, shown as a ring 6, from which depends loosely a snap-hook 7. The clencher-tube 8,

which may be cast of metal, is preferably formed of two semi-cylindrical sections 8^a and 8^b, hinged together to adapt them to be opened and closed, one section carrying, midway between its ends, a rigid catch 9 and the other a spring-pressed hook 9^a for releasably engaging the catch. On the upper end of the section 8^a extends a lip 10 containing an opening 10^a at which to engage the snap-hook. In the opposite end of the same tube-section is provided an upwardly tapering recess 11, about which the edge is rolled, as represented at 12, and in the upper end of the section 8^b is formed, thus diagonally opposite the recess 11, a similar recess 11^a provided with a rolled edge 12.

The user straps the belt about his waist, when the clencher-tube hangs as represented in Fig. 1. After mounting the stage of a suspended scaffold, he opens the tube on its hinges and closes it about the usual hanging guide-rope forming part of a scaffold-equipment and represented at 13, in which condition the hook and catch fasten the sections together. The diameter of the rope being considerably less than that of the clencher-tube, there is no binding between the two by the movements of the user in working on the scaffold-stage, since the tube will slide freely up and down the rope.

Should the scaffold drop, as by breaking or unfastening of the suspending ropes on either or both ends, the simultaneous dropping of the workman's body will tilt the tube 8 upwardly and cause it to engage the guide-rope at the diagonally opposite recesses 11 and 11^a and turn the intermediate rope-section at an angle to its length, thereby firmly clutching the rope and by thus preventing the tube from sliding down the latter hold the weight of the body of the workman, who may then grab the rope in his hands to right himself and simultaneously right the tube and let himself down, hand over hand, to the ground or other alighting point.

The turned or rolled edges 12 present rounded surfaces to the rope 13 to avoid engaging therewith sharp edges of the tube in its movements along the rope and present to the latter rounded edges to facilitate those movements.

I realize that considerable variation is possible in the details of construction thus specifically shown and described, and I do

not intend by illustrating a single specific or preferred embodiment of my invention to be limited thereto; my intention being in the appended claims to claim protection upon all the novelty there may be in my invention as broadly as the state of the art will permit.

What I claim as new and desire to secure by Letters Patent is:—

- 10 1. In a safety device of the character described, a clencher-tube to surround the guide-rope in a scaffold equipment, having recesses diagonally opposite each other in its opposite ends to engage and clench the rope.
- 15 2. In a safety device of the character described, a clencher-tube to surround the guide-rope in a scaffold equipment, said tube being formed of tube-sections hinged together and provided with fastening means at their opening and closing edges, and said sections having recesses respectively in their upper and lower ends, diagonally opposite each other, to engage and clench the rope.
- 20 3. In a safety device of the character described, a clencher-tube to surround the guide-rope in a scaffold equipment, having recesses diagonally opposite each other in its opposite ends to engage and clench the rope and provided with rolled edges about the recesses.
- 25 4. A safety device of the character described comprising, in combination, a belt, a flexible depending hanger on the belt, and a clencher-tube suspended on the hanger to surround the guide-rope in a scaffold equipment.

Copies of this patent may be obtained for five cents each, by addressing the "Commissioner of Patents, Washington, D. C."

ment and having recesses diagonally opposite each other in its opposite ends to engage and clench the rope.

5. A safety device of the character described, comprising, in combination, a belt, a flexible depending hanger on the belt and a clencher-tube to surround the guide-rope in a scaffold equipment, said tube being releasably suspended on the hanger and formed of tube-sections hinged together and provided with fastening means at their opening and closing edges, the tube-sections being provided respectively on their upper and lower ends with clenching means operating, by turning the tube from its normal pendent position, to clenchingly engage said rope.

6. A safety device of the character described, comprising, in combination, a belt, a flexible depending hanger on the belt, and a clencher-tube to surround the guide-rope in a scaffold equipment, said tube being formed of tube-sections hinged together and provided with fastening means at their opening and closing edges, said sections having recesses respectively in the upper and lower ends, diagonally opposite each other, to engage and clench the rope, and one of said sections having a perforated lip on its upper end for connection of the tube with said hanger.

FREDERICK A. VOIGT.
